UNITED STATES PATENT OFFICE.

EDWARD W. COOK, OF LOS ANGELES, CALIFORNIA, ASSIGNOR OF ONE-HALF TO
EDWARD I. FIELD, OF LOS ANGELES, CALIFORNIA.

COOLING TOWER.

Application filed April 27, 1927. Serial No. 187,016.

My invention is a cooling tower usually used for cooling water in industrial and other operations.

An object of my invention is the construction of a cooling tower particularly adapted for cooling water in industrial operations in which the tower is made in a series of units which may be connected together to form a tower of any height desired or if it is desired to decrease the height the units may readily be removed one after the other until the desired amount of cooling of the water is obtained.

A more particular object of my invention is the construction of a cooling tower having a series of louvers, these being arranged in rectangular or other suitable shape in units, and each unit set of louvers having a mounting to allow stacking of the various units one on top of the other, the mounting forming a rigid structure and spacing the louvers the proper distance apart.

More specifically an object of my invention is the construction of louver units having corner legs or brackets, these legs or brackets supporting an upper louver unit on the unit immediately below and each corner leg where it attaches to a louver unit forming the bearing surface for the next unit above.

In constructing my tower I form the louver units preferably of sheet metal, such as galvanized iron, the lower edge of the units being spaced inwardly from the upper portion so that when the units are stacked to form a tower a proper air circulation may be obtained. The corner legs or brackets are preferably formed angular, and of sheet metal, extending along the upper edge of a louver unit and having a lower part which may be riveted to a louver unit next below. These sheet metal legs have braces which are bent inwardly and rest on the underneath louver unit, thus giving a rigid support independent of the bolting or riveting of the units together.

My invention will be more readily understood from the following description, together with the drawings, in which:

Figure 1 is a perspective view of a cooling tower constructed in accordance with my invention.

Figure 2 is a detail vertical section on the

line 2—2 of Fig. 1 in the direction of the arrows.

Figure 3 is a detail elevation of a corner of the tower.

Figure 4 is a horizontal corner detail on the line 4—4 of Fig. 2 in the direction of the arrows.

Figure 5 is a top plan view of a corner post or bracket.

Figure 6 is an inside elevation of such post or bracket, taken in the direction of the arrow 6 of Fig. 5.

In constructing my tower I preferably have a tray 11, which may be constructed in any suitable manner and is preferably made of sheet metal, and above this tray I secure a plurality of louver units 12. Each of these units is preferably constructed of sheet metal having sides 13 with a short vertical section 14 at the top and an inturned flange 15 which may be doubled over in the form of an outward fold 16. The lower part 17 of each side wall below the vertical part 14 is inclined inwardly and at the lower extremity there is an inwardly turned flange 18 forming the lower edge 19 of the louver unit. The lower part of the walls are inclined inwardly at a sufficient angle so that the space 20 between the inside edge 21 of the flange 15 of a lower unit is sufficient to allow free flow of air. The lower edge 19 is also preferably in a plane below the flange 15 to prevent outward blowing of water. The corners 22 of the louver units preferably have a seamed joint but these corners may be connected in any suitable manner.

Attached to the corner of each louver unit at the top is a leg or bracket 23. I find a suitable structure for this leg or bracket may be made of sheet metal having a main leg portion 24 with an inwardly turned flange 25 at the top, this flange fitting over the flange 15 of the louver unit at the corners, the legs being bent with right angular corners 26 for a rectangular type of louver. Rivets or other fastenings 27 secure the upper part of the leg to its louver unit on the vertical part 14 of the side wall. The foot 28 of each of the legs extends downwardly over a leg next below, as indicated by the numeral 29 in Figs. 1 and 3, and is secured by rivets or the like 30 which extend

through such leg part of an upper leg and unit being supported on a unit next below, through the upper part 31 of a lower leg and also through the vertical part 14 of the louver walls, such connection being clearly shown in Figs. 2, 3 and 4.

In order to brace the legs and to support an upper louver unit independent of the riveted connection I provide brace portions or webs 32 which are formed integral with

10 the sheet metal part of the leg and are bent or inclined inwardly so that each of these braces has its lower edge 33 resting on top of the flange 25 of the leg structure on the louver unit next below. This edge 33 preferably is positioned at right angles to the sides of the louver unit.

In some cases it is desirable that the leg or bracket 34 on the lower louver unit be longer than the others so as to extend downwardly into the tray 11, resting on the floor of such tray, and being secured at the corner of the tray by rivets 35.

The louver units may be made up with corner legs or brackets attached to each unit 25 and such units may be stacked up one on top of the other, riveting or otherwise securing an upper leg to the unit next below and so on until a sufficient height of tower is obtained, or if desired the legs can be attached 30 to the louver units after the structure is built up, in which case the louver units may be conveniently packed for shipping by stacking them one inside of another. The legs or brackets are also of such character 35 that they may be stacked together in a convenient manner for shipping.

From the above construction it will be seen that I have developed a simple type of cooling tower that is adapted for many 40 types of water or other liquid cooling. The leg or bracket structure may be adapted to wooden louvers as well as to sheet metal louvers. Also, if desired, the leg structures may be made of wood or other material suitably shaped so that each louver unit may be built up one on top of the other.

Various changes may be made in the principles of my invention without departing from the spirit thereof, as set forth in the 50 description, drawings and claims.

I claim:

1. A cooling tower having a plurality of louver units, corner structures connected to each unit, said corner structures of an upper unit resting on a unit next below.

2. A cooling tower having a plurality of louver units, corner structures connected to each unit, said corner structures of an upper unit resting on a unit next below, and means to positively secure the supporting corner structure of an upper unit on the louver unit next below.

3. A cooling tower comprising in combination a plurality of louver units each unit having a series of legs, the legs of an upper

through such leg part of an upper leg and unit being supported on a unit next below, the legs of an upper unit overlapping the legs of a lower unit, and having means to positively secure the said legs together.

4. A cooling tower comprising in combination a plurality of louver units arranged in a stack, each unit having legs, means at the lower end of each leg to positively secure same to a louver structure next below, and a brace on each leg engaging the upper part 70 of the louver structure next below.

5. A cooling tower comprising in combination a plurality of louver units arranged in a stack, each unit having a corner leg formed of sheet metal bent at an angle to fit two sides of the corner, and means to secure each leg of a louver structure to the louver structure next below.

6. A cooling tower comprising in combination a plurality of louver units arranged 85 in a stack, each unit having a corner leg formed of sheet metal bent at an angle to fit two sides of the corner, means to secure each leg of a louver structure to the louver structure next below, and inwardly turned braces 90 on the edge of each sheet metal leg extending over the top of the louver structure next below.

7. A cooling tower comprising in combination a plurality of units arranged in a 95 stack, each unit having a corner leg formed of sheet metal bent at an angle to fit two sides of a corner, each leg having inwardly turned flanges at the top to engage over the top of a louver structure, and rivets securing the lower end of each leg to a louver structure next below.

8. A cooling tower comprising in combination a plurality of units arranged in a stack, each unit having a corner leg formed 105 of sheet metal bent at an angle to fit two sides of a corner, each leg having inwardly turned flanges at the top to engage over the top of a louver structure, and rivets securing the lower end of each leg to a louver structure next below, and a pair of braces on each leg formed by inturned bends of the edge metal, the lower edge of such braces fitting 110 on top of the louver structure to which the leg is secured at the bottom.

9. In the art described a unit in a cooling tower comprising a louver structure with sides converging inwardly and downwardly, corner legs formed of sheet metal bent at an angle to fit two sides of the corner, the 120 upper part of said legs being secured to the louver structure and the lower part of said legs having means to secure same to a lower louver structure.

10. In the art described a unit in a cooling 125 tower comprising a louver structure with sides converging inwardly and downwardly, corner legs formed of sheet metal bent at an angle to fit two sides of the corner, the upper part of said legs being se- 130

cured to the louver structure and the lower part of said legs having means to secure same to a lower louver structure, and braces formed by inwardly turned sides of the sheet metal of the legs, the lower edges of said braces being adapted to fit on top of a lower louver unit.

11. A cooling tower having a plurality of sheet metal louver units arranged in a stack, each unit having side walls inwardly converging, with an inwardly converging upper flange, sheet metal legs bent to fit two sides

of each corner, said legs having flanges extending over and secured to the flanges of the wall structures of the louver units, means 15 to secure said legs at the bottom to a louver structure next below, and inwardly turned braces on the sides of the sheet metal legs having lower edges to fit on top of the flange of a leg of a louver unit next below. 20

In testimony whereof I have signed my name to this specification.

EDWARD W. COOK.
